UNITED STATES PATENT OFFICE

JOHN J. McCABE, OF CLEVELAND, OHIO

DESIGN FOR A COMBINED CASING FOR A CLOTHES WASHING AND EXTRACTING MACHINE

Application filed July 13, 1931. Serial No. 40,512. Term of patent 14 years.

To all whom it may concern:

Be it known that I, JOHN J. McCABE, a citizen of the United States of America and a resident of Cleveland in the county of Cuyahoga and State of Ohio, have invented a new, original, and ornamental Design for a Combined Casing for a Clothes Washing and Extracting Machine, of which the following is a specification, reference being had to the accompanying drawing, forming part thereof.

The figure is a perspective view of a combined casing for a clothes washing and extracting machine, showing my new design. The opposite side presents substantially the same appearance as the side shown.

I claim:

The ornamental design for a combined casing for a clothes washing and extracting machine, as shown and described.

In witness whereof, I have hereunto set my hand this 10th day of July, 1931.

JOHN J. McCABE.
